UNITED STATES PATENT OFFICE.

OTTO SCHULZE, OF BADEN-BADEN, GERMANY.

LIQUID-FUEL-FEEDING DEVICE FOR INTERNAL-COMBUSTION ENGINES.

Application filed February 18, 1921. Serial No. 446,204.

To all whom it may concern:

Be it known that I, Otto Schulze, engineer, a citizen of the German Republic, residing at Baden-Baden, in the State of 5 Baden, in Germany, have invented certain new and useful Improvements in Liquid-Fuel-Feeding Devices for Internal-Combustion Engines, of which the following is a specification.

10 This invention relates to an improved controlling device for siphons, in which the closing member for the air draw-off nozzle is carried by the guiding-rod of a float-valve and forms an armature for an elec- 15 tromagnet, whereby the reversing action of the float of said float-valve in its upper end position is facilitated while said closing member is kept in its closing position until it is disengaged therefrom by said float re- 20 turning to its lowermost end position.

The accompanying drawing shows in Figs. 1 and 2 respectively a central vertical section, and a diagrammatical cross section through the improved siphon.

25 A float-chamber 1, which is closed toward the atmosphere, carries in its cover the air draw-off nozzle 2, which is embraced by the poles of an electro-magnet 3 in such a way that the nozzle orifice lies in one plane with 30 the lower horizontal pole surfaces. The magnet armature 4 is fixed on the upper end of an intermediary member (tube) 5. Said member is guided on a rod 6 fixed to the bottom of the chamber 1. The float 7 is 35 slideable on said member 5, its up and down movement being limited in upward direction by said armature 4 and in downward direction by a flange 8 on the lower end of said member 5. To the cover of the 40 chamber 1, further, an outer-air-valve 9, and pipe connections 10 and 11 for sucking-off the air and sucking-in the liquid respectively, are attached. At the lower part of the chamber 1 an outlet valve 12 with a 45 valve-disc 13 freely moving on its seat, is provided. A collector (not shown) for the liquid raised is supposed to be located beneath said outlet valve 12.

The operation is as follows:

50 In its inoperative position, the float 7 bears upon the flange 8 of the member 5, while the latter bears upon the upper end 55 of the guiding rod 6. The float assumes then its lowermost position, while the valves 9 and 12 are closed and the nozzle-orifice 2 is open. Upon air being sucked off from

the chamber 1 through the pipe 10, the liquid to be raised ascends through the pipe 11 and enters the chamber 1. Consequently, the float 7 rises and lifts, after a certain 60 time, the member 5 with the magnet armature 4 until the latter is attracted by the poles 3. Thereby, the nozzle orifice 2 is covered and closed. At the same time, the outer-air valve 9 is opened by said armature. 65 The outer air is thus admitted to the chamber 1, so that the liquid raised can flow-off through the outlet valve 12 into the collector underneath. The attractive power of the magnet 3 is so determined that 70 the same safely carries the armature with the member 5. Upon said load being, however, increased by the weight of the float, which descends with the fall of the liquid level until it bears again upon the flange 75 8, the armature is pulled down from the magnet 3 and thus again liberates the air draw-off nozzle 2, while at the same time the outer-air valve 9 is again closed. The proceeding begins then afresh as afore-de- 80 scribed.

What I claim, is:

1. A siphoning apparatus comprising a liquid chamber having at the upper end thereof an air outlet orifice and pipe connection for drawing air therefrom and a pipe connection through which liquid may enter said chamber, and also an air inlet valve, and at its lower end a valve-controlled outlet for liquid; said chamber having enclosed therein a float slidably supported on a vertically slideable member having a magnet-armature mounted thereon, and a magnet above said armature; said vertically sliding member being mounted on a fixed member within said chamber and adapted to be raised and lowered alternately by said float and in ascending to move said armature into operative relation with said magnet and thereby close said orifice and open said air inlet valve, and on its descending movement to release said armature and thereby open said orifice and permit said air inlet valve to close.

2. In a siphon for liquids, in combination, a float-chamber, an outer-air valve, an air draw-off nozzle, and a suction pipe for the liquid to be raised, all attached to the cover of said chamber, a magnet embracing said air draw-off nozzle in such a way that the orifice of the same lies in one plane with the lower pole surfaces of said magnet, an

outlet valve having a valve-disc freely moving on its seat, attached to the lower end of said chamber, a guiding-rod fixed on the bottom of said chamber, an intermediary member guided on said rod and adapted to bear upon the upper end of the same, a flange on the lower end of said member, a float slidably located on said member and adapted to bear upon the flange thereon, and 5 an armature fixed to the upper end of said member and adapted to be lifted with said member by an ascent of said float and to 10 be attracted by said magnet thereby clos-

ing said air draw-off nozzle and simultaneously opening said outer-air valve and to 15 be kept in said position until said member is again loaded by the weight of said float during a descent of the latter, substantially as and for the purpose set forth.

In testimony whereof I affix my signature in presence of two witnesses.

OTTO SCHULZE.
